Corporation, Detroit, Mich., a corporation of
Michigan

Application September 28, 1934, Serial No. 745,970

25 Claims. (Cl. 122—392)

This invention relates to boiler cleaners and has particular reference to a boiler cleaner of the type which is adapted to discharge jets of cleaning fluid adjacent portions of the boiler to be cleaned to dislodge deposits from the same.

One of the primary objects of this invention is to provide a boiler cleaner of the above mentioned character which is provided with a blower element adapted to be projected into the boiler during the blowing operation and adapted to be retracted to a stored position exteriorly of the boiler during the intervals when cleaning fluid is not being discharged from the same whereby the blower element may be utilized in the hottest part of the boiler without danger of the blower element burning out.

A further object of this invention is to provide in a boiler cleaner of the above mentioned character, a single means which when actuated, will cause the blower element to make a complete travel into and out of the boiler, the blower element being adapted to discharge cleaning fluid during this entire travel.

The invention has as a further object the provision of indicating means which will clearly show at all times the position of the blower element.

Still further the invention contemplates the provision in a boiler cleaner of the above mentioned character of a blower element adapted when retracted to be stored in a relatively small space whereby the boiler cleaner may be installed even though the alley space between adjacent boilers or between boiler side walls and building walls is substantially limited.

Numerous other objects and advantages of this invention will become more apparent as the following description proceeds particularly when reference is had to the accompanying drawings wherein

Fig. 1 is a semi-diagrammatic side view of a boiler showing a boiler cleaner constructed in accordance with the teachings of this invention associated with the same;

Fig. 2 is a semi-diagrammatic sectional view taken substantially on the line 2—2 of Fig. 1 and showing the blower in its projected position;

Fig. 3 is a top plan view of the blower shown in Fig. 2, the parts of the blower being in fully retracted position;

Fig. 4 is a longitudinal sectional view taken substantially on the line 4—4 of Fig. 3;

Fig. 5 is an enlarged side elevational view of the blower;

Fig. 6 is a sectional view taken substantially on the line 6—6 of Fig. 5;

Fig. 7 is a sectional view taken substantially on the line 7—7 of Fig. 5;

Fig. 8 is a diagrammatic view showing the 5 wiring diagram of the electrical control means utilized with the blower illustrated in Fig. 2;

Figs. 9 and 9A constitute a side elevational view partly in section showing a slightly modified form of construction;

Fig. 10 is a sectional view taken substantially on the line 10—10 of Fig. 9;

Fig. 11 is an enlarged plan view of a portion of the structure shown in Fig. 9;

Fig. 12 is a sectional view taken substantially 15 on the line 12—12 of Fig. 11; and

Fig. 13 is a diagrammatic view showing the wiring diagram of the electrical control means utilized with the boiler cleaner shown in Fig. 9.

At the high ratings at which steam boilers 20 are now generally operated and particularly when certain types of coal are utilized, slag is formed on the lower generating tubes of the lower deck to such an extent that the gas passages between the tubes become completely 25 blocked in a short time. Because of the high temperatures in the fire box below these tubes, it is impossible to utilize any device for removing this slag that cannot be withdrawn or otherwise removed between blowing or cleaning periods. The present invention therefore contemplates the provision of a projectable and 30 retractable blower nozzle or element which is exposed to the high temperatures within the boiler only during the blowing period when the cleaning fluid used is ample to keep all the exposed parts at a temperature well below that at which they would be damaged.

Further, since the available alley space between boilers or between boiler side walls and 35 building walls is frequently quite limited, it is important that the blower element require a minimum amount of space in its retracted position. The present invention therefore provides a telescopic blower element which, when retracted, projects exteriorly of the boiler only a short distance.

Referring then particularly to the drawings wherein like reference characters designate corresponding parts throughout all views, there is 40 diagrammatically illustrated in Fig. 1 of the drawings a standard type water tube boiler designated generally by the reference character 15. As illustrated, this boiler includes a casing 16, a cross drum 17, upper and lower decks of gen- 45

55

erating tubes designated by the reference characters 18 and 19 respectively, and a superheater 20. The numeral 21 designates generally the fire box or combustion space of the boiler located 5 as illustrated, directly below the lower deck 19 of the generating tubes. To maintain these tubes clean, a blower 25 is located approximately in the position illustrated in the drawings, this blower being constructed in accordance with the 10 teachings of this invention.

Referring now particularly to Figs. 2, 3 and 4 of the drawings, wherein the blower 25 is shown more in detail, the numeral 26 designates a boiler wall, this wall being provided with an opening 27, 15 in which a wall box 28 is mounted. Secured to this wall box and projecting exteriorly of the boiler wall is a housing 29 and secured to this housing and projecting away from the boiler wall is a cylindrical casing 30 to the outer end of which 20 is secured a cap 31.

Fixed, as by welding or the like to the cap 31 and projecting longitudinally of the housing 29 and casing 30, is a pipe or conduit 35. The outer end of this pipe projects beyond the cap 31 and 25 is threaded as at 36 to provide for the attachment thereto of a cleaning fluid supply pipe. The pipe 35 is on its exterior surface, threaded throughout its length as designated by the reference character 37 and is also provided with a 30 longitudinally extending keyway 38, for a purpose which will hereinafter be more fully described.

The numeral 40 designates a bearing which is 35 slidably mounted on the pipe 35 but which is held against rotation with respect to this pipe by a key 41, which engages in the keyway 38 in the pipe 35. Fixed to the bearing 40, as at 42, and surrounding the pipe 35 is a tube 43, this tube being also threaded throughout its length as designated by the reference character 44. It will 40 be apparent that the tube 43 is fixed against rotation by virtue of its connection through the bearing 40 to the non-rotatable pipe 35 but that the tube 43 may move longitudinally with reference to the pipe 35.

45 The blower element proper comprises a nozzle 50 and tube sections 51 and 52. The nozzle 50 is provided with oppositely directed discharge orifices 53 and the nozzle is secured as by welding or the like, to the inner end of the tube 51. The 50 opposite end of tube 51 is secured to a nut 54 which engages the threads on the tube 43. Further, the tube 51 is provided in its outer surface with a longitudinally extending keyway 55 in which is engaged a key 56 carried by the tube 52.

55 The tube 52 is secured at its outer end as at 60, to a nut 61 which has threaded engagement with the outer surface of pipe 35. Further, the tube 52 is provided with a longitudinally extending keyway 61 in which a key 62 is engaged, this 60 key being carried by a worm wheel 63 which is located in the housing 29. Within the wall box a suitable bearing 64 is provided to support the overhanging load of the tubes 51 and 52 when the latter are extended. Additional bearings 65 and 66 are also provided, the bearing 65 acting to reduce the friction of tube 52 turning in casing 30 and the bearing 66 being adapted to reduce the friction of tube 52 turning on stationary bearing 40.

70 Suitably secured to the casing 30 is a motor 70, which by means of a chain 71 drives a shaft 72. This shaft carries a worm 73 which engages the teeth 74 on the worm wheel 63 to drive the latter.

With the structure as thus far described, it 75 will be apparent that the motor 70 will drive worm

wheel 63 and this worm wheel being splined as it is to tube 52 will drive the latter. Rotation of tube 52 will cause the nut 61 to travel longitudinally of pipe 35 to thus project tube 52, bearing 40, and threaded tube 43. As brought out before, tube 43 5 is fixed against rotation, while tube 51 is rotated with tube 52 by virtue of the splined connection between these two tubes. Thus rotation of tube 52 will rotate tube 51 and cause nut 54 to travel longitudinally of stationary threaded tube 43. 10 Thus it will be apparent that for each rotation of tube 52 nut 61 will travel longitudinally of pipe 35 one thread while nut 54 will travel longitudinally of tube 43 one thread. The nozzle 50 is therefore advanced a distance equal to twice the pitch of 15 the threads on pipe 35 and tube 43 and, assuming the pitch to be one-half inch, the nozzle 50 having two outlets gives two blowings for each inch of travel. The inside diameter of tube 52 is slightly larger than the outside diameter of tube 20 51 and there is enough steam leaking between tubes 35 and 43 and 43 and 51 that is forced out between tube 51 and 52 to keep these tubes cool during the blowing operation. When tube 51 is fully projected beyond tube 52, it is cooled 25 by the cleaning fluid passing through the nozzle 50.

Preferably a small amount of heavy cylinder oil is pumped into the blower through the cleaning fluid inlet before each blowing operation to 30 provide the lubricant necessary for the moving parts of the blower.

It constitutes a feature of this invention to provide an indicating means to indicate the position of the nozzle 50 and for this purpose the 35 following structure is provided. Suitably journaled at one side of the casing 30 and extending longitudinally thereof, is a shaft 80, this shaft being threaded throughout its length as indicated by the reference character 81. Formed on one 40 end of this shaft is a worm wheel 82 which is engaged by a worm 83 formed on the end of shaft 72.

Engaging the threads 81 is a nut 85 and this 45 nut is prevented from rotating by virtue of an extension 86 which projects through a slot 87 formed in casing 88 which encloses the shaft 81. An indicating member 89 is carried by the projection 86 and being disposed exteriorly of the casing 88 indicates at all times the position of the nozzle 50.

The nut 85 is also utilized to control the flow of 50 electric current to the motor 70 and for this purpose the following structure is provided. Mounted for limited longitudinal movement in bearings 90 is a rod 91 and fixed to the ends of this 55 rod are lugs 92 adapted to be engaged by the nut 85 when the latter reaches the ends of its travel. Also carried by rod 91 is a sleeve 93 which engages arm 94 of a yoke 95, this yoke carrying a lug 96 which engages arm 97 of a double throw switch 98. It will be apparent that as the nut 85 reaches 60 the ends of its travel longitudinally of shaft 80 it will engage one or the other of lugs 92 and impart a slight longitudinal movement to rod 91. 65 This movement will cause sleeve 93 to throw arm 97 to thus actuate switch 98, the direction of movement of the switch arm 97 being dependent upon the direction of movement of rod 91. For 70 manually shifting the rod 91 to effect a reversing of motor 70 before the blower reaches its fully projected position, if such is desired, there is provided a bell crank lever 99 pivotally mounted on a suitable bracket and so arranged that its one end may be swung into engagement with the ad- 75

5 adjacent end of rod 91 to impart movement to the same.

10 The switch 98 may be a standard reversing switch by which the motor 70 is controlled, the usual arrangement being a push button which 5 closes the forward circuit to the motor thus causing the blower to be projected until the blower reaches its extreme projected position. The switch is then automatically actuated to reverse 10 the motor 70 thereby retracting the blower, the switch being again actuated when the blower is fully retracted to thus stop the motor.

15 The electrical circuit which controls the motor is diagrammatically illustrated in Fig. 8 as comprising the switch 98 having the actuating arm 97, this switch controlling contacts 100, 101 and 102. The circuit also includes a switch 103 preferably of the self-opening push button type this switch controlling contacts 104 and 105.

20 Current is obtained from a suitable source by way of conductors 106, 107 and 108, conductor 108 leading directly to the motor 70. Current from source 106 flows through terminal 109 to 101 then to 100 then to coil 110 and to terminal 104 and when switch 103 is closed the current flows through terminal 105 to terminal 111 and back to conductor 107. This will energize the coil 110 closing bridges 112 and 113 connecting 109 to 114 and 115 to 111 thus completing the circuit to the 25 motor from conductor 106 and back through conductor 107. At the same time current will flow from 115 to coil 110 through conductor 116 thus maintaining coil 110 energized after switch 103 is allowed to open, the coil remaining energized 30 as long as 100 is in contact with 101.

35 To reverse the motor, switch 97 is thrown over by movement of sleeve 93 to break the contact between 101 and 100, de-energizing coil 110 and breaking the contacts between 109 and 114, 115 and 111 thus stopping the motor. Contact is now 40 made between 101 and 102 coil 117 is energized actuating the bridges 118 to bridge terminals 119, 119^a, 119^b and 119^c. Current now flows from source 106 to the motor by 109, 119^c, bridge 118 and contact 119^b and from source 107 to the 45 motor by contact 111, 119, bridge 118 and contact 119^a.

50 With the blower in its retracted position, the several switches are in the positions indicated. The switch button 103 which may be located at any desired point may now be actuated to close the circuit as above mentioned causing the motor to so rotate tubes 51 and 52 of the blower as to cause a forward travel of nozzle 50 to its projected position. Coil 110 maintains the circuit closed when the push button switch is released.

55 As the blower reaches the end of its forward travel, sleeve 93 actuates switch 98 to close the contact between 101 and 102 and to break the circuit between 100 and 101. This breaks the circuit to coil 110 and closes it to coil 117 thus reversing the motor as above indicated. When the blower reaches its fully retracted position, switch 98 is again actuated to break the circuit between terminals 101 and 102 and close the circuit between terminals 100 and 101, the circuit then being ready for a second operation. The motor however, will not again start until push button switch 103 is again closed.

70 In Figs. 9 to 13 inclusive, a slightly modified form of construction is illustrated. Referring then particularly to these figures of the drawings, it will be noted that the structure includes a wall box 28', a housing 29', and a cylindrical casing 75 30' closed at its outer end by a suitable cap 31'.

The blower itself includes the nozzle 50', the tube sections 51' and 52', these tube sections being associated with each other in the manner previously described and being adapted when rotated to be projected by the cooperating threaded pipes 35' and 43'. As thus far described, the blower is in all respects identical with that previously described.

75 In this modified construction however, the tube 52' is rotated by a second tube 120, this tube being splined to the tube 52' as at 121. The tube 120 is rotated by a gear 122 driven by a pinion 123 fixed to the end of a shaft 124, this shaft being driven by the motor 70' through reduction gearing 125 and 126. It will be understood that as thus far 15 described rotation of the shaft 124 by motor 70' will effect a longitudinal travel of the blower element to its projected or retracted position depending upon the direction of rotation of the motor.

20

25 For the purpose of manually retracting the blower in the event that the motor 70' should fail, there is preferably provided a sheave wheel 130, this sheave wheel being secured to the shaft 124 as clearly illustrated in Fig. 9 of the drawings. A 25 chain 131 engaging the sheave wheel is accessible from the floor of the boiler room in accordance with the usual practice.

30 For the purpose of indicating the position of the blower nozzle 50' there is provided a quadrant shaped plate 135, this plate being provided with indicia 136 which indicates in feet the extent of projection of the blower nozzle 50'. Co-operating with the indicia 136 is an indicating arm or arrow 137, the rear end of this arm being 35 secured to a shaft 138 by which the arm is actuated. For actuating the shaft 138, the shaft 124 is provided with an elongated gear 140 adapted to mesh with and drive gears 141 and 142. Gear 141 is fixed to and drives a shaft 143 this shaft 40 having its outer surface threaded as indicated by reference character 144. Gear 142 has a hub which is threaded to engage the threads 144 on shaft 143 and the hub of this gear is also provided with a groove 145 to receive a yoke 146. 45 This yoke is attached to one end of arm 137, the other end of this arm being secured to the shaft 138 as clearly indicated in Fig. 12 of the drawings.

50 In the operation of this indicating device, the shaft 144 is driven in fixed relation to the shaft 124 through the gears 140 and 141. Gear 142 is also driven by gear 140 but gears 141 and 142 have an unequal number of teeth and gear 142 is rotated on shaft 143 so that there will 55 always be a lateral movement of gear 142 on shaft 143. This movement of gear 142 is transmitted to the indicating arm 137 and the parts are so proportioned that the position of the indicating end of arm 137 with reference to the indicia 136 accurately indicates the distance in feet the nozzle 50' is projected.

60 The arm 137 is also utilized for controlling the supply of electric current to the motor 70' and for this purpose the end of arm 137 is provided with an insulated tip 150 adapted to actuate switches 151 and 152 which are clamped to the edge of the plate 135. These switches are preferably removably clamped to the plate so that they may be located in any desired position 65 to thus control the extent of travel of the blower. As in the first described form of construction, the switches are so arranged that after the motor has been started by the momentary closing of a push button switch located at any desired point, 70

60

70

75

80

85

90

95

the blower will be projected forwardly until the limit of its forward movement is reached, whereupon switch 151 will be actuated to reverse the movement of the motor. When the blower reaches its retracted position the switch 152 will be actuated to open the reversing circuit to the motor and to stop travel of the blower in the reserve direction.

In Fig. 13 the electric circuit is diagrammatically illustrated as including the switches 151 and 152, a magnetic reversing switch designated generally by the reference character 155, a hand switch 156 for connecting the system to the source of electrical supply and suitable manually controlled switches, 157, 158 and 159. The switch 157 is the starting switch, the switch 158 is a reversing switch and the switch 159 is a stopping switch and these switches are all preferably located on a panel remote from the blower where-20 by the actuation of the blower may be manually controlled at the will of the operator if desired, instead of employing the automatically operating reversing and stopping switch about to be described.

25 Switch 152 includes contacts 165 and 166, while switch 151 includes contacts 167, 168 and 169. The arrangement is such that the motor can only be started to project the blower by momentarily actuating the push button starting switch 157. When the blower has reached the predetermined forward position, arrow 137 moves contact 168 until it contacts with contact 169, thus making contact with the reverse side of the motor magnetic reversing switch 155. On ac-30 count of the interlocking construction of this switch, however, the motor is not reversed until the arm 137 has moved contact 168 far enough to break the contact of this contact 168 with contact 167. As soon as this contact is broken, 35 however, the motor is reversed and the blower is moved to its retracted position.

As the blower reaches its retracted position, the arm 137 moves contact 165 away from contact 166 thus opening the reversing circuit and 40 stopping travel of the blower. The blower may thereafter only be started by actuating the push button starting switch 157.

From the above it will be apparent that the invention provides a telescopic blower in which 45 the blower nozzle makes a complete in and out travel rotating all the way during this travel and discharging cleaning fluid adjacent parts of the boiler to be cleaned. The actuation of the blower is initiated by a single means namely, the push 50 button since actuation of this push button causes the blower to travel to its outer position and then to return to its original retracted position.

The invention further includes indicating 55 means for indicating the projected position of the blower and means whereby the extent of projection of the blower may be varied at the will of the operator.

For the sake of convenience, the invention 60 has been described as being embodied in a boiler cleaner for cleaning parts of a boiler. It will be apparent however, that the inventive principles disclosed may be incorporated in a device for cleaning similar types of apparatus and it is to be therefore understood that the term "boiler" 65 wherever used in the specification or claims is to be construed as meaning a fluid heater or heat transfer apparatus of any character, while the term "boiler cleaner" is to be construed as meaning a cleaner for cleaning any such apparatus.

While the invention has been described with some detail, it is to be understood that the description is for the purposes of illustration only and is not definitive of the limits of the inventive idea. The right is reserved to make such 5 changes in the details of construction and arrangement of parts as will fall within the purview of the attached claims.

What we claim as our invention is:

1. In a fluid heater cleaner, a blower element 10 mounted for movement to projected and retracted positions, means for moving said blower element to said positions, means for initiating the actuation of said moving means, and means for thereafter controlling and continuing the operation 15 of said moving means to cause the same to move the blower element from its retracted to its projected position and to then automatically return the blower element to its retracted position.

2. In a fluid heater cleaner, a blower element 20 mounted for movement to projected and retracted positions, means for moving said blower element to said positions, means for initiating the actuation of said moving means, and means actuated by said moving means for thereafter 25 controlling and continuing the actuation of the moving means to cause the same to move the blower element from its retracted to its projected position and to then automatically return the blower element to its retracted position. 30

3. In a fluid heater cleaner, a blower element mounted for movement to projected and retracted positions, a motor for moving said blower element to said positions, a driving connection between said motor and said blower element for 35 moving the latter from the former, a control means for said motor adapted to effect a reversal of said motor after a predetermined projection of said blower element, and means connecting said control means and said driving connection 40 to actuate the former from the latter.

4. In a fluid heater cleaner, a blower element mounted for movement to projected and retracted positions, a motor for alternately moving 45 said blower element to said positions, a control means for said motor, and means actuated in synchronism with said blower element for actuating said control means to cause the latter to effect a reversal of said motor after a predetermined projection of the blower element. 50

5. In a fluid heater cleaner, a blower element mounted for movement to projected and retracted positions, a motor for moving said blower element to said positions, a control means for said motor, means including a threaded shaft 55 and a travelling nut on said shaft for actuating said control means, and a connection between said threaded shaft and said motor for actuating the former from the latter.

6. In a fluid heater cleaner, a blower element 60 mounted for movement to projected and retracted positions, and electrically actuated means including a motor and control means therefor for moving said blower element to said positions, said control means being responsive to movement of 65 the blower element and acting to reverse the motor after a predetermined movement of the blower element.

7. In a fluid heater cleaner, a blower element 70 mounted for movement to projected and retracted positions, an electric motor for moving said blower element to said positions, means for initiating the actuation of said electric motor, and means automatically operating after the operation of said electric motor is initiated to cause 75

said electric motor to move said blower element to its projected position and to then reverse the electric motor whereby the same returns said blower element to its retracted position.

5. 8. In a fluid heater cleaner, a blower element mounted for movement to projected and retracted positions, an electric motor connected to said blower element for moving the same to said positions, a control for said motor operating to reverse the motor after the blower element has been projected a predetermined amount, and a driving connection between said motor and said control means for actuating the latter from the former.

15. 9. In a fluid heater cleaner, a blower element mounted for movement to projected and retracted positions, means for moving said blower element to said positions, means controlling said moving means to cause the same to return the blower element to its retracted position after the blower element has been projected a predetermined amount, and means for adjusting said control means to vary the projection of said blower element.

25. 10. In a fluid heater cleaner, a blower element mounted for movement from projected to retracted positions, a motor for moving said element to said positions, means actuated by said motor for indicating the extent of projection of said blower element, and a control for said motor actuated by said indicating means.

35. 11. In a fluid heater cleaner, a blower element mounted for movement to projected and retracted positions, an electric motor, a driving connection between said electric motor and said blower element for moving the latter from the former, an indicating means driven by said connection for indicating the extent of projection of the blower element, a control means for said motor operating to reverse the actuation of said motor after said blower element has been projected a predetermined amount, and means for actuating said control means by said indicating means.

40. 12. In a fluid heater cleaner, a blower element mounted for movement to projected and retracted positions, an electric motor for moving said blower element to said positions, a driving connection between said electric motor and said blower element for moving the latter from the former, a threaded shaft mounted for rotation, means for rotating said shaft from said driving connection, a nut threaded on said shaft and adapted to travel longitudinally thereof upon rotation of the shaft, indicating means carried by said nut for indicating the extent of projection of the blower element, means for initiating the actuation of said electric motor, a control means adapted to reverse the electric motor after the blower element has been projected a predetermined amount and adapted further to stop the actuation of said electric motor when the blower element has been retracted, and means for actuating said control means by said traveling nut.

45. 13. In a telescopic blower, a pair of pipe sections arranged for rotation and for telescopic movement one within the other, a nozzle carried by one of said pipe sections, means for rotating said pipe sections, and means operating upon rotation of said pipe sections to move both of said pipe sections axially and to project the inner pipe section beyond the outer pipe section.

50. 14. In a telescopic blower, a pair of pipe sections mounted for rotation and for telescopic movement one within the other, a nozzle carried by one of said pipe sections, a pair of threaded

tubes fixed against rotation, and nuts carried by said pipe sections and engaging the threads of said tubes whereby upon rotation of said pipe sections both of said pipe sections are moved axially and one of said pipe sections is telescopically moved relative to the other.

55. 15. In a telescopic blower, inner and outer pipe sections, a nozzle carried by one end of said inner pipe section, means for rotating said outer pipe section, a splined connection between said inner and outer pipe sections whereby the inner pipe section is rotated by the outer pipe section but is adapted for axial movement relative thereto, a pair of tubes disposed within said inner pipe section, said tubes being disposed one within the other and having their outer surfaces threaded, a nut fixed to said outer pipe section and threadedly engaging the outer surface of said inner tube, a nut carried by said inner pipe section and threadedly engaging the outer surface of said outer tube, and means fixing said tubes against rotation whereby upon rotation of said pipe sections the pipe sections are both moved axially while the inner pipe section is additionally moved axially relative to the outer pipe section.

60. 16. In a fluid heater cleaner, a blower element mounted for movement to projected and retracted positions, a power driven means for moving said blower element to said positions, a driving connection between said power driven means and said blower element for moving the latter from the former, a control means for said power driven means adapted to effect a reversal of the actuation of said power driven means after a predetermined projection of said blower element, and means connecting said control means and said driving connection to actuate the former from the latter.

65. 17. In a fluid heater cleaner, a blower element mounted for movement to projected and retracted positions, a power driven means for moving said blower element to said positions, a control means for said power driven means, and means actuated in synchronism with said blower element for so actuating said control means that it causes the power driven means to retract the blower element after movement thereof to a predetermined projected position.

70. 18. In a fluid heater cleaner, a blower element mounted for movement to projected and retracted positions, a power driven means connected to said blower element for moving the same to said positions, and a control means for said power driven means operating to reverse the actuation of said power driven means after the blower element has been projected a predetermined amount and operating further to stop the actuation of said power driven means when the blower element has been retracted.

75. 19. In a fluid heater cleaner, a blower element mounted for movement to projected and retracted positions, a power driven means for moving said blower element to said positions, means for initiating the actuation of said power driven means to cause the same to project the blower element, and control means actuated by said power driven means operating to reverse the actuation of said power driven means after the blower element has been projected a predetermined amount and operating further to terminate the actuation of said power driven means after the blower element has been retracted.

80. 20. In a fluid heater cleaner, a blower element mounted for rotation, means operating upon rota-

- tion of said blower element to cause the same to be projected or retracted dependent upon the direction of rotation of the blower element, a power driven means connected to said blower element
- 5 for rotating the same, means for initiating the actuation of said power driven means to cause the same to rotate the blower element in such a direction that the blower element will be projected, and a control means operating to automatically reverse the actuation of the power driven means after the blower element has been projected a predetermined amount to cause the power driven means to reverse the rotation of the blower element to thus cause the blower element
- 10 to be retracted, said control also operating to automatically terminate the operation of said power driven means when said blower element has been retracted.
21. In a fluid heater cleaner, a blower element
- 20 mounted for movement from projected to retracted positions, means for moving said blower element to said positions, a quadrant having indicia thereon, a pointer movable relative to said quadrant and cooperating with the indicia thereon for indicating the extent of projection of the blower element, means connecting the element moving means and the pointer for actuating the latter from the former, and means actuated by the pointer for controlling the actuation of
- 25 said blower element moving means.
22. In a fluid heater cleaner, a blower element mounted for movement from projected to retracted positions, a motor connected to said blower element for moving the same to said positions, a control for said motor operating to reverse the motor after the blower element has been projected a predetermined amount, and means actuated in synchronism with said blower element for actuating said control means.
- 30 23. In a fluid heater cleaner, a blower element
- 35

mounted for movement to a plurality of positions, a power-driven means for moving said blower element to said positions, means for indicating the extent of movement of the blower element, and a control for said power-driven means actuated by said indicating means.

24. In a fluid heater cleaner, a blower element mounted for movement from projected to retracted positions, means for moving said element to said positions, and means for indicating the extent of projection of said blower element, said means including a shaft rotatable in synchronism with the movement of the blower element, an elongated gear on said shaft, a second shaft, a pair of gears on said second shaft arranged to be 10 driven by the elongated gear on the first shaft, one of the gears on the second shaft being fixed to the second shaft and the other gear on the second shaft having threaded engagement with the second shaft, the last mentioned gear on the second 15 shaft having a different number of teeth from the other gear on the second shaft, an indicating pointer, and a connection between said indicating pointer and the gear which is threaded on the second shaft whereby said pointer is actuated 20 upon movement of the gear longitudinally of the second shaft.

25. In a fluid heater cleaner, a blower element mounted for movement to projected and retracted positions, power-driven means for moving said 30 blower element to said positions, a control means for said power-driven means, means including an axially movable shaft for actuating said control means, abutments on said shaft, and a member movable longitudinally of said shaft upon movement of said blower element arranged to engage 35 said abutments to axially move said shaft and thus actuate the control means.
